UNITED STATES PATENT OFFICE

97,763

DESIGN FOR A COMBINED AMPLIFIER AND PROJECTOR CABINET

Joseph Erwood, Chicago, Ill., assignor to The Webster Company, Chicago, Ill., a corporation of Illinois

Application May 13, 1935, Serial No. 56,799

Term of patent 7 years

To all whom it may concern:

Be it known that I, Joseph Erwood, a citizen of the United States, residing at Chicago, in the county of Cook and State of Illinois, have invented a new, original, and ornamental Design for a Combined Amplifier and Projector Cabinet, of which the following is a specification, reference being had to the accompanying drawing, forming part thereof, in which—

Figure 1 is a perspective view of the cabinet in closed condition; and

Fig. 2 is a perspective view of the cabinet in open condition.

I claim:

The ornamental design for a combined amplifier and projector cabinet, as shown.

JOSEPH ERWOOD.
